UNITED STATES PATENT OFFICE.

EDWIN S. VOTEY, OF DETROIT, MICHIGAN.

PNEUMATIC PIANO ATTACHMENT.

SPECIFICATION forming part of Letters Patent No. 650,285, dated May 22, 1900.

Application filed January 25, 1897. Renewed February 5, 1900. Serial No. 4,065. (No model.)

To all whom it may concern:

Be it known that I, EDWIN S. VOTEY, a citizen of the United States, residing at Detroit, in the county of Wayne, State of Michigan, 5 have invented a certain new, useful, and valuable Improvement in Pneumatic Piano Attachments, of which the following is a full, clear, and exact description.

This invention relates to pneumatic piano 10 attachments, and has for its objects, first, to provide a self-playing piano attachment of practical and economical construction which can be quickly applied to and removed from any piano; second, to provide means for in- 15 closing the key-levers of this style of attachment when not in use; third, to provide means carried by the attachment for engaging the under side of the piano-keyboard to more firmly support the attachment in posi- 20 tion, and, fourth, to provide for this and similar devices an improved automatic regulator for the pneumatic motor.

From above it may be noted that some of the special features of construction of this 25 invention pertain solely to a separable self-playing piano attachment and that other constructions are applicable to any form of pneumatic musical instrument.

In the accompanying drawings, which form 30 a part of this specification, Figure 1 shows a transverse vertical section taken centrally through the entire instrument and also showing the front ends in section of the keys of a piano to which my attachment is applied. 35 Fig. 2 shows a front view of my exhaust-chamber, part of the front board being removed, with two sets of my primary and intermediate pneumatics. Fig. 3 is a transverse vertical section through lines X X of Fig. 2. 40 Fig. 4 is a similar view through lines Z Z of Fig. 2.

In the following detailed description I will employ numerals of reference to indicate upon the drawings the parts referred to, the same 45 reference-numeral recurring in the two or more views indicating the same part differently shown.

The operating mechanism of my device is inclosed within a case 1, which has a general 50 resemblance to a small organ-case, its only novel feature being a lid 2, hinged at points 3 to the back-board 4, and which lid serves

the double purpose of closing the rear longitudinal opening in the case when the attachment is not in use and permitting of end 55 pieces 5, secured to said lid, to directly or through the adjustable block 6 thereon engage the under side of the keyboard 7, and thus prevent the attachment from jumping upward when it is attacking a number of the 60 piano-keys 8 9 at any time, as in playing a heavy chord.

In order to elevate or lower the attachment so that its key-strikers 10 11 will exactly sit over the piano-keys 8 9, I provide rollers 12 65 under the four corners of the case 1 and set said rollers in an adjustable frame 13, which extends up into the case and has a vertical movement through the slots 14 in its back working over the screws 15, said vertical 70 movement being effected by screwing or unscrewing the bolt 16, working through the fixed frame 17, as shown in Fig. 1.

At the lower rear end of my attachment I provide two-part pedal-levers, the inner part 75 18 being pivoted at point 19 and the other part consisting of the outwardly-extending piece 20, which has a lateral adjustment upon the inner part 18 by reason of the single connecting-screw 21, which secures the two parts 80 rigidly together when in proper adjustment, so as to contact with the pedals 22 of the piano. The rear piece 20 of the two-part pedal-levers is given a vertical adjustment to accommodate it to the piano-pedal 22 by reason of the 85 adjustable buttons 18^a on the vertical rod 19^a, the lower end of which is threaded. It will be apparent that by screwing the buttons 18^a up or down on the said rod 19^a the inner piece 90 of the pedal-levers will be likewise moved up or down and the outwardly-extending end 20 of said levers, tilting on its pivot 19, given a corresponding movement up or down with relation to the piano foot-pedals 22.

Supposing the attachment to be in operative position—*i. e.*, so adjusted that its key-strikers 10 11 and its pedal-levers 20 properly sit over the piano-keys 8 9 and piano-pedals 22—then after placing the perforated note-sheet 23 in proper position the performer commences by placing his feet upon the foot-pedals 24 and working them alternately in the usual way, and these through the connecting-straps 25 26 working over the segmental 100

lever 27, pivoted at point 28, alternately open and close the exhausters 27^a, and these in turn exhaust the main bellows 28^a, all in an old and well-known manner.

5 The main bellows 28^a, comprising the stationary board 29 and movable board 30, has the usual interior bed-spring 31, tending to keep the bellows opened, and even though the exhausters be kept going so rapidly as to entirely exhaust the bellows 28^a and compress the spring 31 the latter effects but a slight increase in the exhausting power of the bellows through the ordinary flap-valve (not shown) when said spring is but partly compressed, 15 whereas by securing a rod 33 to the lower end 34 of the movable board 30, allowing said rod to slide through the lower end 35 of the long lever 36, pivoted at point 37, until the button 38^a upon said rod 33 engages the lower end 35 20 of said lever 36 at about the time that the regular or primary spring 31 is one-half compressed, then from this point it takes considerable more power to further exhaust the bellows 28, because a further movement of 25 its board 30 must be attended by a movement of the lever 36, having a heavy spring 37^a secured to and tending to prevent an inward movement of the upper end 38 of said lever 36. As a consequence, of course, the bellows 30 30^a upon being exhausted against both its primary and secondary springs will in turn exhaust through the ordinary flap-valve much more rapidly than before, resulting in a more forcible operation of the pneumatics operated 35 from said bellows and a heavier striking of the piano-keys and in this way permitting a variation of touch or strength of stroke independent of the action of the piano-pedals.

The secondary spring just described, together with several modifications, forms the subject-matter of a separate application filed simultaneously herewith and bearing Serial No. 622,239, the general adaptation and importance of this mechanism seeming to warrant my covering it in a distinct application and without combining it with the various parts herein shown.

The pneumatic motor 39, connected by the pitman 40 to the driving-pulley 41, is of any desirable form, its speed being controlled by the amount of air sucked therethrough. The duct 42 forms communication between said motor 39 and the exhaust-chamber 43, the intermediate chamber 44 serving as a convenient place to locate the slide-valve 45, which partly and variably covers the opening 46, according to the degree of movement of the bellows-board 30, to which latter it is connected by the pitman-rod 47, all as clearly shown in Fig. 1. The purpose of thus automatically controlling the slide-valve 45 from the movement of the bellows-board 30 is to prevent an acceleration of the speed of the motor 39 when the degree of exhaust of the main bellows 28^a increases, which increase would ordinarily exhaust a larger amount of air through the opening 46; but by the arrangement shown

the area of this opening 46 is decreased as the power of the bellows increases, and thus avoids any change in the speed of the motor whenever the power of the bellows varies. The driving-pulley 41 is belted to the driven pulley 48, carrying the pinion-gear 49, meshing with the gear 51 of the take-up roller 52, the speed of which may be varied in any desired manner, it being the object of the mechanism just described to prevent an indiscriminate variation of speed of said take-up roller or its motor, as it is frequently desired in rendering a piece of music to increase the power of the bellows or stroke without changing the speed of the motor or tempo.

It now remains only to describe the special construction and arrangement of pneumatics through which the piano-keys 8 and 9 are depressed and which, perhaps, can be better understood from an examination of Figs. 2, 3, and 4, which show large detailed views of the same and from which it will be seen that I employ a primary pneumatic 53, an intermediate pneumatic 54, and a power-pneumatic 55, all controlled from and the first two named arranged within the single exhaust-chamber 56. Any pneumatic required to strike a piano-key a sufficiently-hard blow cannot be properly controlled by a primary pneumatic which is itself controlled by an opening in a note or music-sheet of one-sixteenth diameter, because the valve, such as 54^a, of a power-pneumatic like 55 is too heavy to be rapidly moved by such a small and delicate primary pneumatic 54. I overcome this difficulty by providing a secondary or intermediate pneumatic to be directly operated by the small primary pneumatic 53 and arranging the said intermediate pneumatic to control the heavy valve 54^a of the power-pneumatic 55. To these ends I form six exhaust-chambers 56, all disposed vertically with relation to each other, as shown in Fig. 1, and each chamber, as shown in Figs. 2, 3, and 4, having arranged therein a series of primary pneumatics 53, having the leader-tubes 57 connected to the ducts 58 of the tracker-board 59, the note-sheet 23 passing over said tracker-board 59 and acting as a valve for said primary pneumatic—i. e., so long as an imperforate portion of the note-sheet covers the inlet 60 of the tracker-board leading to said pneumatic the latter remains inactive; but the moment a perforation in the note-sheet passes over its inlet the pneumatic succumbs to the sucking tendency of the exhaust-chamber 56, within which it is located, and is instantly inflated. Arranged directly above said pneumatic 53 is a valve-chamber 61, which has a duct 62 running diagonally down to and communicating with the interior of the pneumatic 54. Connected to and operated by the primary pneumatic 53 is a puppet-valve 63, comprising the stem 64 and the disks 66, so that when said primary pneumatic 53 opens it raises said puppet-valve and allows external air to enter under the upper disk 66 into the valve-cham-

ber 61 and from thence through the duct or channel 62 into the intermediate pneumatic 54, which, being located in the exhaust-chamber 56, is immediately inflated, as was 5 the primary pneumatic 53, and, like it, operates the puppet-valve 54^a, located directly above it. This puppet-valve 54^a upon being lifted by the movement of the intermediate pneumatic 54 establishes a communication 10 through the channel 64, between the exhaust-chamber 56 and the power-pneumatic 55, which instantly causes the latter to collapse or close with great force, owing to the area of the communicating openings. Projecting 15 outwardly from the heel of the pneumatic 55 is an extension-rod 65, having its extreme end connected to the downwardly-projecting striker-rod 10 or 11, the lower fleted end 67 of which is regulated to stand directly over 20 its respective piano-key 9.

Having now given a detailed description of the various parts of my invention and the manner in which said parts operate and co-operate to perform their function, what I 25 claim as new, and desire to secure by Letters Patent both in conjunction with and separable from an attachable and detachable device, is—

1. A separable pneumatic piano attachment 30 comprising an inclosing case having an opening in its rear wall adapted to receive the keyboard of a piano, a lid or cover adapted to close said opening, and arranged when open to engage the under side of a piano-keyboard 35 to support the attachment in operative position, vertically-disposed striker-rods arranged in the casing and having their lower ends terminating near the upper part of the said opening, a bellows, exhausters, motor,

note-sheet holder, tracker-range, and pneumatics inclosed within the case, and foot-pedals for operating said mechanism, substantially as described.

2. In a separable piano attachment, a lid so hinged as to inclose the key-striking levers 45 when not in use and adapted to protrude under the keyboard of the piano when the attachment is shoved up to the latter, for the purpose described.

3. In a separable piano attachment of the 50 class herein described, the combination with the inclosing case having an opening in its rear wall, a lid adapted to close said opening, and adjustable blocks or plates carried by said lid, and adapted to project under the 55 keyboard of a piano when the attachment is in position for operation.

4. In a musical instrument, the combination with the main bellows, of the exhausters mounted upon the stationary board of said 60 main bellows, an exhaust-chamber 43, also mounted upon said stationary board and communicating with the said main bellows, an intermediate chamber 44, arranged upon and opening into said exhaust-chamber, a slide-valve 65 operating to control said opening, a horizontal rod connection 47, between said slide-valve and the movable board of the main bellows, a pneumatic motor, and a port or passage leading from the intermediate 70 chamber to said motor, substantially as described.

In testimony whereof I affix my signature in the presence of two witnesses.

EDWIN S. VOTEY.
